SALVAGING AND LIFESAVING DEVICE FOR
SUNKEN VESSELS

Oscar S. Carpenter, Cloverdale, Ind.

Application August 31, 1942, Serial No. 456,810

4 Claims. (Cl. 114—16.5)

This invention aims to provide novel means whereby a buoy may be attached, releasably, to a submarine beneath the surface and out of commission, the construction being such that the buoy may rise to the surface of the sea, at the will of an operator, the buoy carrying with it a flexible conduit whereby air may reach the sunken submarine.

The invention aims to provide novel means for opening the buoy, when it is at the surface, to permit the entrance of air into the conduit. A further object of the invention is to supply novel means for holding the buoy releasably assembled with the submarine.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:

Fig. 1 shows in elevation, a device constructed in accordance with the invention;

Fig. 2 is a vertical sectional view showing the buoy in position on the submarine, together with means for holding the buoy in that position;

Fig. 3 is a section in a plane parallel to the keel of the vessel, most parts appearing in top plan;

Fig. 4 is an elevation in which the observer is presumed to be within the conning tower;

Fig. 5 is a section disclosing the means for mounting and controlling the air conduit;

Fig. 6 is a longitudinal section of the upper portion of the buoy, the buoy valve being closed;

Fig. 7 is a view similar to Fig. 6 but showing the buoy valve in open position.

The numeral 1 marks the deck of a submarine, one wall of the conning tower being designated by the numeral 2. The space within the conning tower is designated by the arrow I, and the space without the conning tower is marked by the arrow O.

It appears in Fig. 1 that a guide 3 is provided, the guide being disposed preferably at right angles to the keel line of the submarine, the lower end of the guide being secured to the deck 1,

the guide being sustained from the deck by downwardly diverging braces 4.

The numeral 5 designates a buoy, including a body 6 which may be cylindrical, the body being supplied at its end with legs 7, adapted to rest on the deck 1. The body 6 of the buoy 5 is provided with an offset socket 8 (Fig. 1) adapted to receive the upper portion of the guide 3, to hold the buoy in the upright position shown in that figure. The buoy 5, which preferably is made of steel and is adapted to withstand any reasonable pressure, has a lower, tapered end 26, and an upper tapered end 9.

Passing to Figs. 6 and 7, it will be observed that a thimble 10 is threaded into the upper portion of the tapered end 9 of the buoy 5, the thimble having a valve seat 11, and being provided at its upper end with an outstanding flange 12.

Resilient, downwardly diverging detent arms 14 are provided, and are secured at their lower ends to the buoy 5 in any desired way. If preferred, the lower portions of the detent arms 14 may be bound between the upper end of the tapered part 9 of the buoy and the flange 12 on the thimble 10. The thimble 10 carries an upwardly diverging guide cage 15.

A valve stem 16 is mounted for reciprocation in the guide cage 15, and is equipped at its lower end with a valve 17, shaped for reception in the seat 11. A compression spring 18 surrounds a portion of the valve stem 16, the upper end of the spring engaging the upper portion of the guide cage 15, the lower end of the spring engaging the valve 17. The function of the spring 18 is to maintain the valve 17 in closed position. At its upper end, the valve stem 16 is supplied with a downwardly tapered head 19, adapted to cooperate with the detent arms 14 in a manner to be pointed out hereinafter.

The valve mechanism and associated parts are received within a hood 20, including a downwardly flaring skirt 21, attached removably to the tapered end 9 of the buoy by securing devices 22, spacers 23 being mounted on the securing devices, between the skirt 21 and the portion 9 of the buoy 5.

Figure 1 shows that one end of a flexible element 24 is secured at 25 to the tapered lower end 26 of the buoy 5. The flexible element 24 is wound about and terminally secured to a reel 27, shown in Figs. 2 and 3.

The reel 27 is secured to a shaft 28, journaled in a bearing bracket 29 on the deck 1 and in a gland 30 carried by the wall 2 of the conning

tower. The shaft 28 enters the conning tower, and, within the conning tower, a ratchet wheel 31 is secured to the shaft.

As shown in Fig. 4, and in Fig. 3, the ratchet wheel 31 cooperates with a pawl 32 forming part of a cuff 33 mounted to rock on a spindle 34 carried by the wall 2 of the conning tower, the cuff having an operating handle 35. Rotation may be imparted to the shaft 28 by any suitable means, for example, a hand wheel 36 secured to the shaft.

A flexible tube 37 (Fig. 3) is provided, one end of the tube being connected at 38 (Fig. 1) to the tapered lower end 26 of the buoy 5. The flexible tube 37 is an air conduit, and it is wound about a reel 39, secured to a shaft 40. The shaft 40 is journaled in a bearing bracket 41, mounted on the deck 1 of the submarine, and in a gland 42 mounted on the wall 2 of the conning tower. The shaft 40 enters the conning tower and may be rotated by any suitable instrumentality, for instance a hand wheel 43.

The shaft 40 is provided, as shown in Fig. 5, with a longitudinal bore 44, and a coupling 45 in the body of the reel 39 establishes communication between the bore and the inner end of the tube or air conduit 37. The numeral 46 indicates, diagrammatically, a combined suction and blower device, located at any chosen position on the submarine and connected to a conduit 47 which, in turn, is assembled detachably with the end of the shaft 40, through the instrumentality of a union 48.

Let it be supposed that the flexible element 24 is wound upon the reel 27, the pawl 32 being engaged with the ratchet wheel 31. The legs 7 of the buoy 5 are held down on the deck 1, and the buoy cannot rise. The valve 17 is in the closed position of Fig. 6. The single-bore air conduit includes the part 37, which is now wound upon the reel 39. The conduit 47 is not at this time connected to the shaft 40, because the shaft must rotate when the buoy 5 rises and it is not desirable to twist the conduit 47; although, if desired, the union or coupling 48 might afford a rotatable connection between the conduit and the shaft 40, such a construction being a mere mechanical expedient, readily understood without specific delineation.

Assuming that the submarine is perilously submerged, the operator frees the pawl 32 from the ratchet wheel 31 of Fig. 4, by means of the handle 35. The buoy 5 now rises to the surface, the flexible element 24 paying off the reel 27, and the air conduit 37 paying off the reel 39. When the buoy 5 arrives at the surface, it designates the locus of the submarine, since the buoy is connected to the submarine by the flexible member 24.

It is clear that, as the buoy 5 rises to the surface, it should be closed against the entrance of water. That condition exists because the valve 17 of Fig. 6 is held closed by the spring 13, the detent fingers 14 resting against the head 19 of the stem 16, at the wider, upper end of the head.

After the buoy 5 has reached the surface, the valve 17 must be opened, so that air can pass downwardly, through the buoy and through the air conduit 37 and the bore 44 of the shaft 40. In order to accomplish this result, the conduit 47 is connected to the shaft 40 by way of the union 48, and the blower 46 creates pressure in the entire air line, and in the buoy 5, underneath the valve 17. The valve 17 is moved to the open position of Fig. 7, and the detent fingers 14 engage underneath the head 19 and hold the valve 17 open.

The skirt 21 prevents spray from entering the buoy 5 if there is a lop running.

The blower 46 then is reversed, so that it will draw in air through the buoy 5 and through the air line, the air being delivered to any desired part of the submarine.

The wheel 36 or its equivalent constitutes means whereby the shaft may be rotated to wind the flexible element 24 on the reel 27, and the hand wheel 43 is used to rotate the shaft 40, to wind the air conduit 37 on the reel 39.

The valve 17 may be moved manually from the open position of Fig. 7 to the closed position of Fig. 6 by removing the hood 20-21, the releasable securing elements 22 permitting such an operation.

The first reel 39 and the second reel 27 constitute means under the control of an operator for so distributing the buoy-strain that all of it comes on the anchor line 24. As a result, the air conduit 37 may be small in diameter, light, and the more flexible. It is not necessary to have an air conduit of bulky nature and strong enough to form a mooring means for the buoy.

Having thus described the invention, what is claimed is:

1. In a salvaging and life-saving device for sunken water-craft, a vessel, a hollow buoy, means for retaining the buoy on the vessel and for releasing the buoy to rise at the will of an operator, when the vessel is submerged, a single-bore air conduit leading from the vessel to the buoy, a single air-admission valve carried by the buoy, said valve constituting a complete closure for the upper end of the buoy, mechanism on the vessel for discharging air under pressure through the conduit and through the buoy, directly against said single valve, to open it by directly applied air pressure, after the buoy has reached the surface, thereby to provide ventilation for the submerged vessel, and mechanism independent of air pressure within the buoy for holding the valve closed while the buoy is rising.

2. In a salvaging and life-saving device for sunken water-craft, a vessel, a hollow buoy, means for retaining the buoy on the vessel and for releasing the buoy to rise at the will of an operator, when the vessel is submerged, a single-bore air conduit leading from the vessel to the buoy, an air admission valve carried by the buoy, said valve, constituting a complete closure for the upper end of the buoy, mechanism on the vessel for first creating air pressure in the conduit and in the buoy, thereby to open the valve, by air pressure applied directly thereto, and then creating suction in the buoy and in the conduit, thereby to draw surface air into the submerged vessel, and mechanism independent of air pressure within the buoy for holding the valve closed while the buoy is rising.

3. In a salvaging and life-saving device for sunken water-craft, a vessel, a hollow buoy, means for retaining the buoy on the vessel and for releasing the buoy to rise at the will of an operator when the vessel is submerged, the buoy having a seat in its upper portion, a cage carried by the buoy, a stem slidable in the cage and having a head at its upper end, an air-admission valve secured to the lower end of the stem and constituting a closure for the seat, a valve-closing compression spring interposed between the cage and the valve, a yieldable detent finger carried by the buoy and cooperating with the head to hold the valve open, an air conduit leading from the vessel to the buoy, and mechanism on the vessel for

discharging air under pressure through the conduit and through the buoy, to open the valve after the buoy has reached the surface, thereby to provide ventilation for the submerged vessel.

4. In a salvaging and life-saving device for sunken water-craft, a vessel, a hollow buoy, a reel located outside the vessel, a flexible element connected to the buoy and wound about the reel, a shaft forming part of the reel and extended within the vessel, releasable means located within the vessel for restraining the shaft against rotation, thereby to hold the buoy against rising, a second reel located outside the vessel, a hollow

5 shaft forming part of the second reel and extended within the vessel, a flexible air conduit wound about the second reel and communicating with the buoy and with the hollow shaft, an air-admission valve carried by the buoy, means for holding the valve releasably closed while the buoy is rising, and mechanism on the vessel and communicating with the hollow shaft, to discharge air under pressure through the conduit and through the buoy, thereby to open the valve after the buoy has reached the surface, and to provide ventilation for the submerged vessel.

OSCAR S. CARPENTER.
